INVENTOR

UNITED STATES PATENT OFFICE

EVERETT MARION LEWIS, OF TULSA, OKLAHOMA

VAGINAL DOUCHE PIPE

Application filed April 2, 1928. Serial No. 266,618.

The invention relates to improvements in vaginal douche pipes in which a stop cock or valve is provided in the internal pipe near its proximal end and a groove or catch is provided in the said internal pipe near its distal end for the attachment of a soft collapsible bulb.

The objects of my invention are, first, to provide a means of using a detachable soft collapsible perforated elastic bulb for the effective non-irritating use of any cleansing vaginal douche solution or application of any medical solution usually recommended for use in the treatment of diseased conditions of the vagina or cervix uteri; second, to provide a practical readily accessible means of cutting off or regulating the flow of a vaginal douche solution into and through a detachable soft collapsible perforated elastic bulb 10 while the said bulb is inserted in the vaginal canal; with the foregoing objects in view I have provided vaginal douche pipes comprising a rigid external pipe and a rigid slidible internal pipe and a stop cock located in the nozzle portion of the rigid slidible internal pipe and have provided a detachable soft collapsible perforated elastic bulb for use in connection with the said vaginal douche pipes. The rigid external pipe has thin walls which 20 are so shaped that there is provided an enlarged proximal and distal end portion, there are no perforations or openings in its walls laterally except a median slot and a right and left side slot to accommodate the stock of a stop cock and to permit of its adjustment and use. The said external pipe serves as a housing for the rigid slidible internal pipe and as a means of controlling and inserting the detachable soft collapsible perforated elastic 30 bulb into the vaginal canal. The rigid slidible internal pipe has thin walls except near its proximal end where there is provided a comparatively thick enlarged portion to accommodate a stop cock, the said pipe has no perforations or openings in its walls laterally except an opening in its enlarged proximal end portion in which there is fitted a stop cock, it has a provision at its proximal end for the attachment of a rubber hose or tubing and 40 has a groove or catch at its distal end which

provides a means of holding the neck of the detachable soft collapsible perforated elastic bulb and retaining the said bulb in position while it is being used with a vaginal douche solution, the said rigid slidible internal pipe 55 together with its stop cock serves to control or regulate the flow of a vaginal douche solution into and through the detachable soft collapsible perforated elastic bulb. The stop cock which I have provided for use in connection with the said vaginal douche pipes and which is located in the nozzle portion of the rigid slidible internal pipe serves as a means of cutting off or regulating the flow of a solution through the nozzle portion of the 60 said pipe. The detachable soft collapsible perforated elastic bulb which I have provided for use in connection with the said vaginal douche pipes is of globular shape and has thin elastic walls which are provided with numerous small perforations to permit of an adequate flow of a vaginal douche solution, the 65 said bulb before use is to be attached in the groove or catch in the distal end of the rigid slidible internal pipe, when it is so attached and when it is inserted into the vaginal canal together with the rigid external pipe and the rigid slidible internal pipe and a vaginal 70 douche solution from a fountain syringe or other container is allowed to flow into it it becomes expanded or rounded out and forms a cushion and at the same time allows a free flow of the douche solution to spray out through the numerous perforations in its expanded walls; the said bulb by its expansion 75 produces an expansion of the walls of the vagina and while being used by an upward and downward movement in the vaginal canal it serves to wipe away or dislodge impurities and by a liquid flowing through its numerous 80 small perforations it serves to effectively cleanse the vaginal canal and cervix uteri by spraying any solution usually recommended or used for a vaginal douche and serves to effectively apply medicine in solution as a 85 treatment for various diseased conditions of the vagina and cervix uteri.

One form of the invention is illustrated in the accompanying drawings, in which Figure 1 is a view of the device as it appears 90

when ready to be inserted into the vaginal canal. Figure 2, a view of the device as it would appear while in use after being inserted into the vaginal canal except the shape of the soft collapsible bulb 3 while in use is variable. Figure 3, a sectional view of the distal ends of pipes 1 and 2 and sectional view of soft collapsible bulb 3 shown as they appear ready to be inserted into the vaginal canal (see Figure 1). Figure 4, a sectional view of the ends of pipes 1 and 2 and sectional view of soft collapsible bulb 3 shown as they would appear while in use after being inserted into the vaginal canal except the shape of the soft collapsible bulb 3 while in use is variable (see Figure 2). Figure 5, a sectional view of internal pipe 2 showing enlarged portion near its proximal end which accommodates stop cock or valve 4. Figure 6, a sectional view of the distal ends of pipes 1 and 2 and sectional view of soft collapsible bulb 3 showing internal pipe 2 in an extended position with soft collapsible bulb 3 collapsed and attached in groove or catch which is provided near the distal end of said internal pipe 2.

The vaginal douche pipes described and claimed in this specification and illustrated by the accompanying drawings may be manufactured of hard rubber or of other hard substances as celluloid, etc., or the pipes may be manufactured of a metallic substance. The soft collapsible bulb 3 which is to be used in connection with the vaginal douche pipes is to be manufactured of soft rubber or of other soft substance which is adaptable to the production of a suitable thin walled collapsible bulb.

The external pipe 1 serves as a housing and as a control for the internal pipe 2 and as a housing and control for the soft collapsible bulb 3. The proximal end of external pipe 1 has an enlarged portion to accommodate the enlarged proximal end portion of internal pipe 2 and the said external pipe 1 has an enlarged portion at its distal end to accommodate the soft collapsible bulb 3. The enlarged proximal end portion of external pipe 1 is provided with a median slot, said median slot has a right and left side slot near its distal end, the said median and side slots accommodate stock of stop cock or valve 4 which is located in internal pipe 2 near its proximal end; the stock of said stop cock or valve 4 is provided with a knob or handle 5 which is to be used in turning said stop cock or valve 4 in cutting off or regulating the flow of a liquid through internal pipe 2, the said knob or handle 5 is also used in pushing the internal pipe 2 backward or forward or from side to side in the external pipe 1. The internal pipe 2 may be pushed backward or forward the length of the median slot in the external pipe 1 by pushing backward or forward on knob or handle 5; when the said knob or handle 5 is pushed forward for a suffi-

cient distance the stock of stop cock or valve 4 to which it is attached may be engaged in either the right or left side slot (see Figure 2) which affords a temporary fixed position of the partly extended internal pipe 2 and of the soft collapsible bulb 3 permitting the said bulb to be used as illustrated by Figures 2 and 4; when said stock of stop cock or valve 4 is not engaged in either of the right or left side slot but pushed forward to the full length of the median slot it produces an extended position of internal pipe 2 which permits of the attachment or removal of the soft collapsible bulb 3 (see Figure 6) which is performed by stretching the neck of the said bulb and drawing it on or off over the distal end of internal pipe 2. In attaching the soft collapsible bulb 3 its neck is stretched and drawn over the distal end of internal pipe 2 until the marginal band of the neck of said bulb reaches a groove or catch which is provided for it near the distal end of internal pipe 2; the marginal band of the neck of said bulb is then allowed to drop into the said groove or catch which retains it in position for use.

The enlarged distal end portion of external pipe 1 serves as a housing or control for soft collapsible bulb 3 while it is being inserted into the vaginal canal; the said bulb first being attached to the distal end of internal pipe 2 is drawn backward in its housing or external pipe 1 where it is retained while being inserted into the vaginal canal, after it is inserted said bulb together with internal pipe 2 is pushed forward by pushing forward on knob or handle 5 until the stock of stop cock or valve 4 reaches the right and left side slots where it is to be engaged in one of the said slots which retains internal pipe 2 and soft collapsible bulb 3 in an extended position as shown in Figures 2 and 4 in which position they are ready for use. The soft collapsible bulb 3 is provided with numerous small openings which permit of an adequate flow of any liquid that is generally used as a vaginal douche, the liquid used enters said bulb through internal pipe 2 from a fountain syringe or other container, said fountain syringe or container being connected by soft rubber tubing or some other kind of soft tubing with the proximal end of internal pipe 2. As the soft collapsible bulb 3 becomes filled with a liquid flowing into it there is produced a rounding out or expansion of the said bulb which forms a soft cushion permitting of its manipulation without irritation or injury to the cervix uteri (the lower and narrow end of the womb) or to the vaginal canal; when the soft collapsible bulb 3 is in use and is rounded out or expanded by a liquid which flows out through its numerous openings the said bulb tends to adapt itself to the contour of the walls of the vagina and aids in cleaning the said walls and also aids in cleaning the cervix uteri by

its wiping effect which is produced by an upward and downward movement of the vaginal douche pipes. The opening through stop cock or valve 4 permits of an adequate flow of a liquid through internal pipe 2 that is generally used as a vaginal douche. Screw plug 6 retains stop cock or valve 4 in position and closes the opening in internal pipe 2 which is provided for assembling said stop

cock or valve 4.

I am aware that prior to my invention vaginal douche pipes have been made for use in connection with fountain syringes and other containers and I am also aware that stop cocks or valves have been made for use in cutting off or controlling the flow of a liquid from fountain syringes and other containers into and through vaginal douche pipes or syringe tips. I therefore do not claim such a combination broadly; but

I claim:

In a vaginal douche nozzle an external pipe, a rigid internal pipe longitudinally slidable therein, a stop cock on said internal pipe to control the flow of a liquid therethrough, a stock portion of said stop cock cooperating with longitudinal and lateral slots in the external pipe to form a bayonet lock holding the inner pipe in a longitudinally adjusted position with regard to the outer one.

EVERETT MARION LEWIS.
